By his Attorneys,

Thomas A. Cross,

Inventor:

UNITED STATES PATENT OFFICE.

THOMAS A. CROSS, OF BARDWELL, KENTUCKY, ASSIGNOR OF FOUR-FIFTHS
TO WILLIAM L. MOSBY, STEVE POLLIVICK, WALLACE WEBB, AND ROBERT
J. YOUNG, OF SAME PLACE.

TRACE-CARRIER.

SPECIFICATION forming part of Letters Patent No. 474,820, dated May 17, 1892.

Application filed July 2, 1891. Serial No. 398,266. (No model.)

To all whom it may concern:

Be it known that I, THOMAS A. CROSS, a citizen of the United States, residing at Bardwell, in the county of Carlisle and State of Kentucky, have invented a new and useful 5 Trace-Carrier, of which the following is a specification.

This invention relates to improvements in trace-carriers; and the objects in view are to 10 utilize the well-known trace-carrying leather loop and to improve the same by the addition of a cheap and simple attachment, to be used in connection with said loop, whereby the chain-trace may be connected to the loop 15 in a simple and readily-detachable manner, so that rubbing of the chain or loop against the sides of the horse is avoided.

With the above objects in view the invention consists in certain features of construction hereinafter specified, and particularly 20 pointed out in the claims.

Referring to the drawings, Figure 1 is a perspective of a trace-carrier. Fig. 2 is a vertical transverse section of the same. Fig. 3 25 is a vertical longitudinal section of the same. Fig. 4 is a detail in perspective of the fastening device and its supporting-plate. Fig. 5 is a detail of the chain-engaging hook.

Like numerals of reference indicate like 30 parts in all the figures of the drawings.

1 designates the back-band, to which is riveted or otherwise connected the usual trace-carrying loop 2.

3 designates a concavo-convex cast-metal 35 plate, which is provided near its center with a pair of perforations 4 and near its opposite ends with a pair of transversely-opposite perforations 5.

In forming the fastener I employ a blank of 40 wire, of suitable rigidity and length, and bend the same at its center, as at 6, forming opposite terminals, and near the central bend bend the terminals parallel to each other and upwardly to form a small hook 7, after which 45 said terminals are downwardly bent, forming a large hook 8 and the shank 9. It will thus be seen that I form a hook within a hook, the small hook serving as a safety-hook to prevent any accidental disconnection of the 50 chain-trace therefrom. After forming the two

hooks the terminals or shanks are passed downwardly through the two opposite perforations 4 near the center of the securing-plate, and said terminals are then longitudinally bent in opposite directions, as at 10, and terminate flush with the ends of the securing-plate. The device as thus constructed is 55 ready for attachment to any ordinary leather trace-carrying loop, and to attach the same it is placed in the bottom of the loop and staples 60 11 inserted in the perforations 5 of the securing-plate, and have their terminals passed through the bottom of the leather loop and clinched upon the under side thereof, so that, 65 as will be apparent, each terminal of the hook is embraced by the securing-plate and opposite terminals of the staples.

In use the trace 12 has one of its links engaged over the main or large hook of the fastener, and, as will be seen, a ready engagement and disengagement may be accomplished between the two, while at the same time the small hook serves to prevent any accidental disengagement. By the employment 70 of such a device the rubbing of the trace 75 against the sides of the horse is avoided and a cheap and simple connection between the trace and loop effected.

Having described my invention, what I 80 claim is—

1. The herein-described improved trace-carrier, the same consisting of the leather loop, a concavo-convex metal securing-plate having a pair of perforations, a wire hook rising from the plate and having its terminals 85 forming the shank passed through the perforations of the plate and laterally and oppositely disposed thereunder, and means for securing the terminals of the shank and the plate in position, substantially as specified. 90

2. The herein-described improved trace-carrier, the same consisting of a leather loop, a concavo-convex metal securing-plate having a central pair and opposite end pairs of 95 perforations, the wire hook consisting of the double vertical shank, the same bent to form the main hook which at its end is bent to form a safety-hook, the shank or terminals of the wire being passed through the central perforations of the securing-plate and later- 100

ally bent under said plate, and the opposite staples passed through the pairs of perforations in the securing-plate and through the leather loop and having their terminals clinched upon the under side of the loop, substantially as specified.

In testimony that I claim the foregoing as

my own I have hereto affixed my signature in presence of two witnesses.

THOMAS A. CROSS.
